UNITED STATES PATENT OFFICE.

ALEXANDER E. LITTLE, OF LYNN, MASSACHUSETTS, ASSIGNOR TO A. E. LITTLE & COMPANY, OF LYNN, MASSACHUSETTS, A FIRM.

ARCH-SUPPORTER.

No. 822,138.

Specification of Letters Patent.

Patented May 29, 1906.

Application filed November 29, 1905. Serial No. 288,603.

To all whom it may concern:

Be it known that I, ALEXANDER E. LITTLE, a citizen of the United States, and a resident of Lynn, in the county of Essex and State of Massachusetts, have invented an Improvement in Arch-Supporters, of which the following description, in connection with the accompanying drawings, is a specification, like numerals on the drawings representing like parts.

This invention relates to that class of arch-supporters which are adapted to be worn on a person's foot instead of within the shoe.

My improved arch-supporter is made of some suitable flexible material—such as cloth, leather, or fiber—and is of a shape to fit under the arch of the foot and is provided with a fastening member which extends over the instep of the foot, thereby securing the arch-supporter to the foot.

The arch of the foot is supported by means of a suitable pad which is carried by the body portion of the arch-supporter, said pad preferably being confined within a suitable pocket located beneath the arch of the foot. By using pads of different thicknesses the arch of the person's foot may be supported more or less, as desired.

In the drawings, wherein I have shown one embodiment of my invention, Figure 1 is a side view of a person's foot with my arch-supporter in position thereon. Fig. 2 is a perspective view of my improved arch-supporter. Fig. 3 is a section on the line z z, Fig. 2. Fig. 4 is a section on the line y y, Fig. 2.

The arch-supporter comprises a body portion 3 of some suitable flexible material—such, for instance, as leather or fiber—and having a shape to fit underneath the arch of the person's foot, as shown in Fig. 1.

Connected to the body portion 3 or forming part thereof is a fastening member 4, adapted to extend over the instep of the foot and by which the device is secured to a person's foot. This fastening member 4 is preferably provided with an elastic portion 5.

The part of the body portion 3 which extends underneath the arch of the foot is provided with a pad-receiving pocket 6, in which a pad 7, of some suitable material, may be placed. This pad-receiving pocket is shown as being closed at the front and back and one side and open on the other side, as at 8, so that the pad 7 may be slipped laterally into the pocket. By using pads 7 of different

heights the arch of the foot may be supported more or less, as desired.

The body portion 3 is preferably shaped so that it incloses and fits around the heel, as at 9, and the device operates, therefore, both as a heel-protector for the stocking and as an arch-supporter for the foot.

The arch-supporter is preferably made of some flexible soft material, such as chamois or leather, and both sides of the pocket are of this same material. No portion of the arch-supporter is stiffened, and the pad is relied upon solely to support the arch by its thickness or body.

It will be noted that the device is worn on the foot, and therefore so long as it is in place the arch of a person's foot is properly supported whether he is wearing shoes or not.

My arch-supporter is very simple and inexpensive to make, and because of the fact that pads of different thicknesses may be used in it the same device may be used for persons who desire more or less support to the arch of their foot. This avoids the necessity of having any metal arch-supporter especially made.

The preferred embodiment only of my invention has been herein illustrated.

Having described my invention, what I claim as new, and desire to secure by Letters Patent, is—

1. An arch-supporter comprising a body portion of soft, flexible material shaped to extend under the arch of a person's foot, the portion of the arch-supporter beneath the arch of the foot being provided with a pad-receiving pocket which is open at one side, and a removable pad to be placed within the pocket, said body portion having an elastic band to extend over the instep of the foot. 95

2. An arch-supporter comprising a body portion made entirely of soft, flexible material and shaped to inclose the heel and to extend under the arch of the foot, the portion beneath the arch of the foot being provided with a pad-receiving pocket open at the side, and a pad removably placed within the pocket. 100

In testimony whereof I have signed my name to this specification in the presence of two subscribing witnesses.

ALEXANDER E. LITTLE.
